UNITED STATES PATENT OFFICE

2,002,120

METHOD OF AND APPARATUS FOR CONDITIONING CIGAR WRAPPER LEAF TOBACCO

Charles G. Maxwell, Louisville, Ky., assignor, by
mesne assignments, to The American Tobacco
Company, a corporation of New Jersey

Application January 27, 1931, Serial No. 511,631

15 Claims. (CL 131—55)

My present invention relates to a new method of and apparatus for conditioning cigar wrapper tobacco leaves to render them soft and pliant, and in the best possible condition, without deterioration, for immediate use in the manufacture of all grades of cigars.

Cigar wrapper tobacco leaves are delivered to cigar manufacturers in so-called "hands" or bundles, consisting of a number of leaves tied together at their butt ends. When received, the leaves are relatively dry and usually some of the leaves are "matted", i. e., in adherent contact with adjacent leaves requiring manual separation before they can be properly conditioned under present conditioning methods. When in a relatively dry state the leaves break easily, especially when separated or unmatted by hand, and as this class of tobacco is expensive, (a large part of it being imported) any breakage of the leaves which will reduce the number of individual cigar wrappers that may be obtained from each leaf becomes a matter of great economic importance to the cigar manufacturer.

Furthermore, the color of the leaves is also of great importance, especially those of a relatively light brown or "mild" color, and as they change color or become darker under the influence of mildly excessive heat and become "spotted" by globules of water, any conditioning method to be acceptable to a careful manufacturer, jealous of his product, must be devoid of such evil influences, and to be commercially practicable the leaves must be uniformly conditioned in the shortest possible time.

The objects, therefore, of the present invention are to provide a distinctly new method of and apparatus for conditioning cigar wrapper leaf tobaccos to render the leaves soft and pliant, without deterioration, which may be carried out continuously and wherein the leaves may be conditioned in a much shorter time than is possible with the methods now generally in use.

Briefly and generally stated, the method consists in continuously and slowly passing the "hands" of leaves, (preferably suspended by their "butt" ends) thru a moving atmosphere having a humidity of from 94 to 98 percent, and a temperature of from 70 to 85 degrees F., and in maintaining the leaves in such humid atmosphere for a period of time sufficient to permit them to naturally absorb or take up sufficient moisture to render them soft and pliant, and may further consist in imparting a lateral swinging motion to the "hands" as they travel through the atmosphere in order that the matted leaves

thereof may become automatically separated and thus permit the moving humid atmosphere to come into direct contact with all portions of every leaf of each hand to thoroughly and uniformly condition the same.

I have demonstrated on a commercial scale that with my new method tobacco leaves may be properly conditioned in from three to five hours, depending upon the kind or character of the tobacco and the velocity and temperature of the current of humid air passing through the treatment chamber, and so far as I am aware no method or apparatus has ever been produced that will effectively do the work in so short a period of time.

In order to enable others skilled in the art to understand and practice my said invention, I will now proceed to describe the same in connection with the attached drawings, in which I have illustrated one form of apparatus for carrying out the method.

Figure 1 is a side elevation of a wrapper conditioning apparatus constructed in accordance with my invention.

Figure 2 is a plan view.

Figure 3 is an end elevation of the apparatus shown in Fig. 1, looking at the right-hand end thereof.

Figure 4 is a transverse section taken on the broken line 4—4 of Fig. 1.

Figure 5 is a longitudinal section taken on the line 5—5 of Fig. 2.

Figure 6 is a detail view showing the gear reduction driving mechanism for advancing the endless chain conveyors.

Figure 7 is a detail view showing the take-up mechanism for the endless chain conveyor.

Figure 8 is an enlarged section showing two of the inlet passages leading to the conditioning chamber.

Figure 9 is a plan view of the mechanism for reciprocating the conveyor chains to impart a swinging movement to the suspended hands of leaves.

Figure 10 is a section on the line 10—10 of Fig. 9.

Figure 11 is a section taken on the line 11—11 of Fig. 9.

Figure 12 is a section taken on the line 12—12 of Fig. 10.

Figure 13 is a section on the line 13—13 of Fig. 12.

Figure 14 is a longitudinal section of a slightly modified form of apparatus.

Figure 15 is a section on the line 14—14 of Fig. 14.

Figure 16 is a transverse section of a modified form of tobacco hand-carrying bar and its clips.

5 Figure 17 is a rear view of one of the clips illustrated in Fig. 16.

Figure 18 is a longitudinal sectional view of one end of the modified form of tobacco hand-carrying bar showing its pivotal or swivel connection with the carrier chains.

10 Referring more particularly to Figures 1, 2 and 5, the reference numeral 1 indicates a relatively long chamber, the walls of which are preferably composed of insulating material of any suitable 15 nature, opposite sides thereof being preferably provided with suitably-spaced sight windows 2, covered with transparent material for observing the interior of the chamber when in working condition.

20 This chamber 2 may be supported by any suitable means, but I prefer to suspend it from the ceiling 3 of the room in which it is installed, and for this purpose any approved supporting means may be employed, such as the metal or other 25 hangers 4.

When thus supported, the space beneath the chamber may be utilized for working or storage purposes. Each end of the chamber 1 is provided with a downwardly and outwardly inclined casing 5 open at its extremity, as shown in Figs. 1 and 5, that to the left of the figures indicating the inlet end of the apparatus, and that to the right indicating the outlet end. Shafts 6 are journaled in the lower end of each of the casings 5, said shafts carrying sprocket wheels 7. Other sprocket wheels are supported on other shafts suitably mounted at the inlet and outlet ends of the chamber 1, said sprocket wheels supporting a pair of suitably trained endless chain conveyors 9, the opposite runs of which are exposed at the inlet and outlet ends of the chamber for a purpose presently to be described.

The chain conveyors 9, may be maintained relatively taut by any suitable slack adjuster, as the toothed idlers 9^a, mounted upon the spring-pressed rod 9^b as more clearly shown in Figure 7.

55 The sprocket wheels 8 for the upper run of the chains are so located within the chamber as to cause the said run of the conveyor to travel through the upper portion of the chamber. The two endless chains 9 are arranged to travel through the chamber 1, and the casings 5 at opposite sides thereof, and said chains carry a plurality of suitably-spaced transverse tobacco "hand" supporting bars 10, as more clearly shown in Figures 10 and 12, each bar carrying a plurality of appropriately-spaced tobacco "hand" gripping devices, such as spring clips, each consisting of a fixed jaw 12, and a movable spring-pressed jaw 13, the said jaws being pivoted at 14, and normally held in gripping position by means of a spring 15. The lower end of the fixed jaw 12 is provided with a series of outwardly-projecting points or projections 16, and the lower end of the movable jaw 17 is curved or arched in cross-section, as more clearly shown in Figure 12, and is longitudinally corrugated or provided with inwardly-extending points or projections, as at 18, so as to firmly grip the butt ends of the 70 "hands" or bundles of leaves to be passed through the conditioning chamber.

The endless chain conveyors 9, with their supporting bars 10, are caused to travel slowly through the conditioning chamber by any suitable slow-speed gearing or driving means, such as the

sprocket chain 19 driven by motor 20, and including any approved type of reducing gearing shown in the present instance as enclosed in housing 20^a, Fig. 6, and also including sprocket chain 21, which drives the large gear 22 mounted upon the shaft 23—all as more clearly shown in Figures 1 and 6.

The length of the conditioning chamber and the speed of the conveyor chains are so proportioned that it requires anywhere from three to 10 five hours for a given point on the chain, as for instance a particular supporting bar 10, to travel entirely through the chamber. This speed is sufficiently slow to permit an operator standing at the inlet end of the machine to load all of the 15 clips of a particular supporting bar with "hands" of tobacco before that bar moves up into its casing 5, and to permit an operator at the outlet end of the apparatus to remove all of the conditioned 20 "hands" of leaves from an exposed supporting bar 20 before it returns into the chamber and during the movement of the conveyor, and without stopping the same. By this arrangement the operation of the apparatus is continuous, the "hands" being fed in at one end and removed at the other. 25

In the particular apparatus illustrated, I have shown the conditioning chamber as made of two sections arranged end to end, each section being provided with an inlet 24 at its bottom, and an outlet 25, at its top, each outlet being housed in 30 a hood 26, and each having communication with the upper part of the interior of the chamber through a plurality of ports or passages 27, located in the top wall thereof. The inlets 24 lead into chambers 28, arranged at the bottom of the 35 conditioning chamber of the apparatus, and communication is had between the chamber 28 and the interior of the conditioning chamber through ports or passages 29, in each of which is mounted a plurality of louvers 30, each having a depending 40 laterally deflecting vane 31, all as more clearly shown in Figs. 5 and 8, the said louvers operating to properly deflect and distribute the currents of humidified air with which the conditioning chamber is supplied from below upward through 45 the suspended "hands" of leaves, and out through the outlets 27.

Any suitable air conditioning or humidifying means may be employed to supply properly conditioned air to the conditioning chamber. In the 50 present instance, I have shown in Figure 2, more or less diagrammatically, two of such conditioning means designated generally by the numeral 32, each having an outlet pipe or a conduit 33, connected with the inlets 24 to the conditioning chamber, and each having an inlet pipe 34 connected to the outlets 25 leading from the conditioning chamber, the arrangement being such that properly conditioned humidified air may be caused to circulate through the conditioning chamber in 60 appropriate volumes and at appropriate speeds, so that the amount of humidified air passing through the chamber may be regulated at will.

As is well understood in the art, each humidifying apparatus, which I have not shown in detail, includes suitable water jets or sprays, sometimes called "air washers", through which air is forced to properly condition the air. As such apparatus is well known in the art, I do not deem it necessary to illustrate or describe the same in 70 detail.

Suffice it to say, in the practice of my new method, I have found that the air to be supplied to the conditioning chamber must have a moisture content of between 94 and 98%. Percentages 75

appreciably below and above these limits will likely defeat the objects of the invention. Likewise, the conditioning air must have a temperature of between 70 and 85° F. The proper temperature is provided preferably by installing suitable heating units (not shown) in the air-moistening or humidifying apparatus. Temperatures appreciably below or above those indicated are also likely to defeat the purposes of the invention, because overheating the tobacco leaves will either discolor them, or cause some other deteriorating effect.

I have found in the practice of my improved method, that it is highly desirable to impart a lateral swinging motion to the hands of leaves as they travel through the conditioning chamber. This not only tends to separate the matted leaves, one from another, but also opens up the individual leaves of the hands, so that the moving current or currents of conditioned air which pass upward through the chamber, attack every portion of the various leaves of the hands, and thus thoroughly and uniformly condition them so that they will be rendered appropriately soft and pliant, ready to be worked in the manufacture of cigars.

One form of means for imparting this lateral swinging motion to the suspended hands of leaves is more clearly illustrated in Figs. 4, 5, 9 and 11, and comprises means for imparting short lateral movements to a section of the upper run of the chain and its supporting bars. This means consists in providing extra supporting sprockets 35 for a section of the upper run of the endless chains 9, said supporting sprockets being carried by longitudinally reciprocating stub shafts 36, mounted in journals 31, carried by brackets 39 at each side of the chamber 1, on opposite sides of the center thereof, as more clearly shown in Figure 10.

The stub shafts 36 are each reciprocated by means of a link 39, eccentrically connected to a disk 40, mounted upon the shaft of a motor 41, as more clearly shown in Figure 10. The link 39 is pivotally connected to an oscillating bar 41, which in turn is secured at its lower end as at 42, to the shaft 36, and at its upper end as at 43, to a reciprocating rod 44, which extends transversely through the upper part of the conditioning chamber, and is connected to the shaft 36, at the other side of the apparatus by means of a strap connection 45, so that the conveyor chain supporting sprockets 35 at opposite sides of the conditioning chamber will be reciprocated simultaneously, thus imparting short laterally-directed vibrations or reciprocating motions to a relatively long section of the upper run of the conveyor chains, this resulting in imparting a sidewise swinging motion to the hands of leaves suspended from the various supporting bars 10, carried by the chain between the uppermost fixed sprockets 8, within the conditioning chamber.

In order to provide for free and practically frictionless movement of the reciprocating shafts 36, which carry the sprockets 35, I provide the bearings 37 for said shafts with anti-friction rollers 46, mounted in suitable grooves in the shafts and their bearings respectively, as more clearly shown in Figure 11.

In the apparatus illustrated in the accompanying drawings, which is a substantial duplicate of a commercial structure I have built and successfully operated, the conditioning chamber 1 is approximately 60 feet long and the speed of the tobacco transporting conveyor is approximately 2 inches per minute. This means that with a

chamber of this length and a movement of the conveyor as specified, it requires about five hours for the hands of leaves to pass through the conditioning chamber, and to be completely and properly conditioned. This conditioning time may be lowered to approximately three hours by increasing the volume of the stream of conditioned air passing through the chamber, always with the understanding that the percentage of humidity and the temperature are not appreciably above or below those heretofore stated.

The length of stroke given the shafts 36 to cause a swinging motion to be imparted to the hands of leaves is about 4 inches, and I prefer to impart from 80 to 100 strokes per minute, although I do not wish to be understood as limiting myself to any length of stroke or number of strokes per minute, nor do I wish to be understood as limiting myself to any particular length of conditioning chamber, or to any particular speed of travel of the conveyor chain. Obviously, these may be varied within limits, without departing from the spirit of the invention; nor do I wish to be understood as limiting myself to the employment of two air-conditioning means associated with each conditioning chamber, as one or more such means may be employed, depending upon the size of the chamber.

An important feature of my new method resides in the fact that the conditioning is performed at temperatures which are the average normal temperatures prevailing in the various working rooms of a factory in which my apparatus, and other machines, are installed, and as the conditioning chamber is open at both ends the tobacco coming from the chamber directly into the room neither sweats nor becomes stiff.

In Figs. 14 and 15 of the accompanying drawings, I have illustrated a slightly modified arrangement of the conditioning chamber. The main difference in this arrangement over that shown in the other views resides in the fact that both runs of the endless chain conveyer travel through the upper part of the conditioning chamber, the hands of leaves in this arrangement being supported by the bars of the lower run of the chains as shown. With this arrangement the upwardly moving currents of humidified air are not in any way deflected by the bars which carry the hands of leaves as in the arrangement illustrated in the first described form of the apparatus. I therefore prefer to use the arrangement illustrated in Figure 14.

In this Figure 14 the numeral 2' indicates the sight windows in the opposite walls of the conditioning chamber, and the numeral 4' indicates the supports for the chamber, the chamber in this instance being supported from the floor instead of being suspended from the ceiling. The numerals 5' indicate the extensions for the endless carrier chains, said extensions being located at the opposite ends of the chamber, and the bottom of each chamber being provided with openings for the chains and their "hand" supporting bars to pass through.

As in the prior construction, the left-hand end of the Fig. 14 construction is the feeding or inlet end, and the right-hand end is the discharge or outlet end of the apparatus. The endless chain carriers 9' travel over the sprockets 8', and the tobacco hand supporting bars are indicated at 10'.

As shown in Fig. 16, I prefer to construct the bars 10' of sheet metal, as such construction is not likely to warp or twist. I prefer to enclose

10

15

20

25

30

35

40

45

50

55

60

65

70

75

or encase the metal bars 10' within an insulating strip or cover of felt or other fabric 11, to guard against condensation of moisture upon the bars.

In Fig. 16, the numeral 12' indicates the fixed 5 member of the hand-butt engaging clip, 13', the movable member or jaw which is pivoted at 14', and 15' indicates the spring for normally holding the movable jaw into gripping relation with the fixed jaw.

10 In Fig. 17 I have shown the rear face of the fixed jaw 12' provided with struck up perforations which form burrs on the outer face of the fixed jaw, which burrs will penetrate the butts of the hands of leaves to more firmly hold them in gripping relation between the two jaws.

15 As shown in Fig. 18, the bars 10' are connected to the chain links 9¹ by means of pins or journals 9'', which affords a pivotal or swivel connection between the bars and the chains so that the bars 20 will not turn over or rotate in their travel about the end sprockets 8¹ located at the opposite ends of the apparatus.

25 As will be seen by referring to Fig. 14, the extensions 5' at the opposite ends of the conditioning chamber support the endless chains in such a way that the lower runs of the chains at each end of the apparatus will expose the tobacco hand-carrying bars and their clips to permit the operator at the feed end of the machine to readily 30 attach the tobacco hands to the clips, and the operator at the delivery end of the machine to readily remove the conditioned hands from the clips.

35 The numeral 24' indicates the inlet end of the chamber 28' into which the conditioned air comes from the air washer or conditioning apparatus, and 29' indicates the openings leading from the casing 28' into the conditioning chamber, 31' indicating the louvre.

40 As will be seen by referring to Figure 15, there are two rows of spaced openings leading from the chamber 28' into the conditioning chamber, and these openings are arranged in spaced relation to permit of a large number of well distributed outlets for the conditioned air so that all portions of the leaves of the suspended hands will be directly attacked by the air.

45 The numeral 26' indicates the casing at the top of the conditioning chamber out through which the conditioned air passes, and numerals 27' indicate the openings leading from the top of the conditioning chamber into the casing 26'.

50 Numerals 35' indicate the laterally reciprocating sprockets which support the lower run of the endless carrier chains, and which impart a side-wise swinging motion to a portion of the lower run of the chains, their bars and the hands of leaves supported thereby, it being understood that the sprockets 35' may be reciprocated by any suitable mechanism, such, for instance, as that illustrated in the prior described arrangement.

55 In the last described arrangement, as in the one previously described, the conditioned air having the humidity and temperature stated, is caused to circulate through the conditioning chamber, into contact with the travelling hands of leaves, and then back to the air moistening or conditioning apparatus, with all of the advantages heretofore referred to, and the additional advantages described with reference to the modified arrangement.

60 It will be understood that according to my method the tobacco leaves do not, at any point in the conditioning operation, come into direct contact with free water such as would tend to

spot or discolor the leaves. Because of this, the tobacco leaves retain their natural color and are not subject to rapid deterioration or rot.

65 While I have described my method as being "continuous", in that the hands of tobacco are moved continuously through the conditioning chamber, I do not wish to be understood as limiting myself to a continuously moving endless conveyor, as the objects of the invention may be accomplished by an intermittently moving conveyor.

70 While I prefer to impart a lateral swinging motion to the hands of leaves as they travel thru the conditioning chamber, because this speeds up the operation and makes for thorough and uniform conditioning of the leaves, I do not wish to be understood as limiting myself to this step in the method, as with some types of tobacco the step may be omitted.

75 My new conditioning method is not to be confused with the well known so-called "ordering" methods now generally employed by manufacturers of various kinds of tobacco products, such as cigarettes, smoking and chewing tobaccos, as such "ordering" methods differ materially in various particulars from my method, and are incapable of accomplishing the results secured by the practice of my method or to be substituted for my method.

80 What I claim is:—

1. The herein-described continuous method of conditioning tobacco leaf wrappers to render them soft and pliant, which consists in continuously passing a succession of suspended hands of leaves into, through and out of a chamber slowly and in direct contact with a current of warm humid air moving thru the chamber, the said air having a moisture content of approximately 96 per cent and in so regulating the conditions of operation that the moving tobacco will be maintained in the presence of the humid atmosphere until it absorbs naturally all the moisture it can assimilate by absorption in such an atmosphere, the temperature of the said atmosphere being such as to substantially retard the formation of water globules such as would tend to spot the leaves.

85 2. The herein-described continuous method of conditioning tobacco leaf wrappers to render them soft and pliant, which consists in continuously passing a succession of suspended hands of leaves into, through and out of a chamber slowly and in direct contact with a current of humid air moving thru the chamber, the said air having a moisture content of approximately 96 per cent, and a temperature of approximately 80 degrees F., and in so regulating the conditions of operation that the tobacco in its travel through and out of the chamber will be maintained in the presence of the humid atmosphere for a sufficient length of time to permit it to absorb naturally all the moisture it can assimilate by absorption in such an atmosphere.

90 3. The herein-described continuous method of conditioning cigar wrapper leaf tobacco to render the leaves soft and pliant, which consists in continuously passing suspended hands of leaves into, thru and out of a conditioning chamber, causing a current of humid air having a moisture content of 96%, and a temperature of approximately 80° F. to pass upward through the chamber and through the traveling leaves, and in imparting a lateral swinging motion to the hands of leaves as they pass thru the said upwardly moving current.

4. In an apparatus for conditioning "hands" of tobacco leaves to render the leaves soft and pliant, a conditioning chamber, means for transporting hands of leaves through said chamber, means for creating and causing a current of humid air having a moisture content of approximately 96 per cent and substantially free of water globules to pass through said chamber, and into contact with the hands of leaves, and means for moving said transporting means and the attached leaves through the chamber at such a speed proportioned to the length of the chamber that the leaves will absorb naturally all the moisture they can assimilate by absorption in such an atmosphere and thus be rendered soft and pliant by their travel thru and out of the chamber in one direction. 10
5. In apparatus of the class described, a chamber having an inlet opening at one end and an outlet opening at the other end, an endless conveyor passing through said chamber and having portions thereof extending through said inlet and outlet openings, means carried by the conveyor for carrying suspended hands of tobacco leaves, means for imparting short lateral reciprocating movements to a portion only of the conveyor as it travels through the chamber to cause the hands of leaves carried by said portion to swing laterally from their suspended butt ends, and means for introducing humid air into the chamber. 20
6. In apparatus of the class described, a conditioning chamber having an inlet opening at one end and an outlet opening at the other end, an endless chain conveyor passing through said chamber, and having portions thereof extending thru and beyond said inlet and outlet openings, means carried by the conveyor for carrying suspended hands of tobacco leaves, means for imparting short reciprocating movements to a portion of the conveyor travelling through the chamber, to cause the hands of leaves to swing laterally from their suspended butt ends, and means for introducing warm humid air into the chamber, having a moisture content of from 94 to 96% and a temperature from 70 to 85° F. 30
7. In an apparatus of the class described, a conditioning chamber having an inlet opening at one end and an outlet opening at the other end, a pair of endless chains trained to move through said chamber, with one run thereof positioned in the upper part of the chamber, bars carried by the chains and arranged transversely of the chamber, means carried by the bars for engaging and holding the butt ends of hands of tobacco, for supporting them in a suspended position, means for imparting relatively short reciprocating movements to a portion only of the upper run of each chain for causing lateral swinging movements to be imparted to the suspended hands of leaves carried by said portion, and means for causing humid air to flow through the chamber and into contact with the suspended leaves. 40
8. In apparatus of the class described, a horizontally-arranged conditioning chamber having an inlet opening at one end and an outlet opening at the other end, a pair of endless chain conveyors passing through said chamber with portions thereof extending through said inlet and outlet openings, means for supporting the upper runs of the chains in the upper portion of the chamber, transverse bars carried by the chains, a plurality of clips attached to each bar, each clip having jaws for gripping the butt end of a hand of leaves, a plurality of spaced inlets leading through the bottom of the chamber, means for producing and causing humid air having a moisture content of approximately 96% to pass upwardly through said inlets and through the chamber and into contact with the leaves travelling therethrough, and a plurality of spaced outlets for the humid air at the upper part of the chamber. 5
9. In apparatus for conditioning cigar tobacco leaf wrappers, a conditioning chamber having an inlet opening at one end and an outlet opening at the other end, a pair of endless conveyor chains passing through said chamber, with portions thereof extending through and beyond said inlet and outlet openings, means for supporting the upper run of the chains to cause them to travel through the upper portion of the chamber, transversely-arranged bars carried by said chains, a plurality of clips carried by each bar for grasping and holding the butt ends of hands of leaves, means for causing the upper run of the chains to reciprocate laterally for the purpose specified, and means for causing a current of humid air having a moisture content of from 94 to 98% humidity, and a temperature of from 70 to 85° F. to pass through said conditioning chamber. 10
10. In apparatus for conditioning hands of tobacco leaves to render the leaves soft and pliant, a conditioning chamber having an opening at each end thereof, means for transporting tobacco "hand" carrying bars through the upper portion of said chamber and slightly beyond each end thereof, spaced means carried by the bars for holding hands of leaves suspended therefrom, slow-speed driving means for advancing the bars slowly through the chamber, and means for creating and causing humid air having a moisture content of approximately 96% and a temperature of approximately 80° F. to flow through said chamber and into contact with the leaves passing therethrough, the construction and arrangement of parts being such that the leaves in their passage through and out of the chamber will be maintained in the presence of the humid atmosphere until they absorb naturally all the moisture they can assimilate by absorption in such atmosphere. 30
11. In apparatus for conditioning hands of tobacco leaves to render the leaves soft and pliant, a conditioning chamber having an opening at each end thereof, endless chains for transporting hands of tobacco leaves through said chamber and beyond each end thereof, spaced means carried by the chains for suspending the hands of leaves therefrom, slow-speed driving means for advancing the chains slowly through the chamber, and means for creating and causing humid air having a moisture content of approximately 96% and a temperature of approximately 80° F. to flow through and out of the chamber, the speed of the chains and the length of the chamber being such that the leaves will remain in contact with the humid air for a sufficient length of time to render them soft and pliant by their travel through and out of the chamber in one direction. 40
12. In apparatus for conditioning hands of tobacco leaves to render the leaves soft and pliant, a conditioning chamber having an opening at each end thereof, endless chains for transporting hands of tobacco leaves through said chamber and beyond each end thereof, spaced means carried by the chains for suspending the hands of leaves therefrom, slow-speed driving means 50
- 75

- for advancing the chains slowly through the chamber, and means for producing and causing humid air having a moisture content of approximately 96% and a temperature of approximately 5 80° F. to flow upwardly through and out of the chamber and into direct contact with the leaves of the suspended hands, the speed of the chains and the length of the chamber being such that the leaves will remain in the humid atmosphere 10 for a length of time sufficient to render them soft and pliant during their travel through and out of the chamber in one direction.
13. In an apparatus for continuously conditioning "hands" of tobacco leaves to render the 15 leaves soft and pliant, a conditioning chamber, means for transporting hands of leaves through one end and out of the other end of said chamber, means for producing and causing a current of warm humid atmosphere substantially 20 free of water globules and having a moisture content of approximately 96 per cent to pass through and out of said chamber, and into direct contact with the traveling hands of leaves, and means for moving said transporting means 25 and the attached tobacco leaves through the chamber at such a speed proportioned to the length of the chamber and the character of the tobacco that the leaves in their travel through and out of the chamber will remain in the humid 30 atmosphere for a length of time sufficient to enable them to naturally absorb all the moisture they can assimilate by absorption in such an atmosphere to render them soft and pliant.
14. A tobacco conditioning apparatus of the 35 class described comprising a chamber having an opening at each end, an endless conveyor sup-
- ported for movement through the chamber with portions thereof extending beyond the said end openings, a housing at each end of the chamber partially enclosing said extending portions of the endless conveyor but leaving a section thereof excised for attaching and removing hands of tobacco leaves during such movement of the conveyor, tobacco hand-supporting bars carried by said endless conveyor and arranged transversely of the chamber, means carried by said 10 bars for gripping the butt ends of hands of tobacco, and means for creating and causing a current of warm humid air having a moisture content of approximately 96 per cent and a temperature of approximately 80 degrees to flow 15 into, through, and out of said chamber.
15. The herein-described continuous method of conditioning tobacco leaf wrappers to render them soft and pliant, which consists in passing a succession of suspended hands of leaves into, 20 through and out of a chamber and in direct contact with a succession of upwardly directed currents of warm humid air moving through the chamber, the said air having a moisture content of approximately 96%, and in so regulating the 25 conditions of operation that the tobacco in its travel through and out of the chamber will be maintained in the presence of the humid atmosphere for a sufficient length of time to permit it to absorb naturally substantially all the moisture it can assimilate by absorption in such an atmosphere, the temperature of the said atmosphere being such as to substantially retard the 30 formation of water globules such as would tend to spot the leaves.

CHARLES G. MAXWELL.
